UNITED STATES PATENT OFFICE.

JOHN B. VAN HOUTEN, OF NEWARK, NEW JERSEY.

DESIGN FOR AN EAR-RING.

SPECIFICATION forming part of Design No. 14,860, dated March 4, 1884.

Application filed November 21, 1883. Term of patent 7 years.

To all whom it may concern:

Be it known that I, JOHN B. VAN HOUTEN, a citizen of the United States, residing at Newark, in the county of Essex and State of New Jersey, have invented and produced a certain new and original Design for Ear-Rings; and I do hereby declare the following to be a full, clear, and exact description of the invention, such as will enable others skilled in the art to 5 which it appertains to make and use the same, reference being had to the accompanying drawings, and to letters of reference marked thereon, which form a part of this specification.

Figure 1 is a front elevation, and Fig. 2 a 15 side view. These are deemed necessary to fully illustrate the design.

The leading feature of the design consists in the ear-ring pendant having the configuration substantially as described. Said pendant 20 is, centrally, shaped as at *a*, in resemblance to a looped band, the extremities of which are brought nearly together at the upper part of the pendant, the extremity nearer the front of the design lying below the back one, so that a 25 portion of the back of the band appears above

the front when viewed in front elevation, as in Fig. 1. The outer portion, *b*, of the pendant is shaped somewhat in resemblance to the letter **U**, or to a horseshoe, bending around the lower part of the central portion of the pendant. The upwardly-extending arms lie laterally adjacent to the band portion. Beneath said band the outer portion projects substantially as shown in Fig. 2 at *c*. 30

What I claim is—

1. The design for an ear-ring, consisting of 35 an ear-ring the pendant portion of which is centrally loop-shaped, around the lower or looped portion of which a U-shaped portion extends.

2. The design for an ear-ring, consisting of 40 an ear-ring having the pendant portion shaped substantially as herein set forth.

In testimony that I claim the foregoing I have hereunto set my hand this 16th day of 45 November, 1883.

JOHN B. VAN HOUTEN.
